CLAIM

The ornamental design for a vaporizer cartridge, as shown and described.

DESCRIPTION

FIG. 1 is a perspective view of the vaporizer cartridge; FIG. 2 is a front elevational view of the vaporizer cartridge of FIG. 1;

FIG. 3 is a rear elevational view of the vaporizer cartridge of FIG. 1;

FIG. 4 is a right side elevational view of the vaporizer cartridge of FIG. 1;

FIG. 5 is a left side elevational view of the vaporizer cartridge of FIG. 1;

FIG. 6 is a top plan view of the vaporizer cartridge of FIG. 1; and,

FIG. 7 is a bottom plan view of the vaporizer cartridge of FIG. 1.

The broken lines in the drawings illustrate portions of the vaporizer cartridge that form no part of the claimed design.
